Van Curtis Dodge

C. A. Snow & Co.

UNITED STATES PATENT OFFICE.

VAN CURTIS DODGE, OF SACRAMENTO, CALIFORNIA.

FOLDING TABLE.

SPECIFICATION forming part of Letters Patent No. 544,846, dated August 20, 1895.

Application filed February 28, 1895. Serial No. 540,103. (No model.)

To all whom it may concern:

Be it known that I, VAN CURTIS DODGE, a citizen of the United States, residing at Sacramento, in the county of Sacramento and 5 State of California, have invented a new and useful Folding Table, of which the following is a specification.

This invention relates to folding tables for general use where it is desirable to provide 10 an article of this nature which can be conveniently stored and readily set up for use when required.

The purpose of the invention is to provide 15 a structure in which the side rails will be adapted to fold upon the table-top and which, when turned into a normal position, can be braced against lateral stress from either side, and will embrace the sides of the legs opposite the end rails as a clamp, and prevent 20 such portion from splitting, which frequently happens in this class of tables when they are subjected to end strain by placing a load upon them in a careless manner. It has been proposed to project the extremities of the end 25 rails beyond the legs and have them enter grooves in the side rails. Such construction has been found objectionable, because the end strain upon the table-top results disastrously to the legs by causing them to split and crack. 30 All these objections are overcome by my invention, and the table, while capable of being packed into a small bundle, is securely braced when set up for use without the necessity of providing irons or braces or like stays other 35 than those usually found in tables as generally constructed.

The improvement consists, essentially, of a folding side rail notched near its end to embrace the sides of the legs opposite the end 40 rails, and in a turn-button or brace pivoted in a notch provided in the upper edge of the said side rail, to be turned crosswise thereof to brace the rail laterally in each direction.

The improvement also consists of the novel 45 features and the peculiar construction and combination of the parts, which hereinafter will be more fully described, and set forth in the claims, and which are shown in the accompanying drawings, in which—

50 Figure 1 is a bottom plan view of the table, showing the leg-section and side rails folded upon the table-top. Fig. 2 is a bottom per-

spective view of the table as it will appear when set up for use. Fig. 3 is an end view showing the table folded into a compact form. 55

The table-top A is divided longitudinally, and has the leg-sections hinged to the under side near each extremity. The leg-sections are similarly constructed, and comprise legs B and end rails C, the latter being centrally 60 divided and hinged together. It will be understood that these leg-sections must be so disposed that when folded upon the table-top the legs B will lie in the same plane and just pass one another, as clearly indicated in Fig. 65 1 of the drawings. This disposition of the leg-sections causes them to be placed a little out of alignment, to admit of the legs of one section passing the legs of the opposite section when folding the two leg-sections, so 70 that all the legs may lie close against the table-top. It has been found necessary to provide the leg-sections at diagonally-opposite points with lateral extensions b, so that the sides of the legs may come in the same 75 plane. The reason for this construction is manifest when it is remembered that the upper portion of the legs enters notches in the side rails, and that the sides of said portion entering the notch are embraced by the side 80 walls of the said notch. The side rails D are hinged to the edge portion of the table-top so as to fold outward, and have notches or 85 grooves d in their inner sides to receive the upper portion of the legs or their extensions b, as hereinbefore stated. A notch 2 is provided in the upper edge of the side rail, preferably at a middle point in its length, to receive a brace or stay 3, which is pivoted midway of its ends in the said notch and is 90 adapted to be turned crosswise of the rails and brace the same laterally in each direction. This brace or stay is formed of the same piece which is cut from the side rail to form the notch 2, and is secured by a screw 95 or bolt to the said side rail so as to be turned when desired and secure the side rail in proper position.

From the foregoing it will be seen that the table can be cheaply and economically constructed, as no expensive irons, fastenings, or braces are required to firmly and rigidly secure the parts in the located position when the table is set up for use. 100

Having thus described my invention, what I claim is—

1. The combination with the table top, of folding leg sections, folding side rails notched 5 in their inner sides to embrace the sides of the leg sections at their upper ends to prevent splitting or cracking, and braces pivoted in notches provided in the upper edges of the said side rails, and adapted to be turned 10 crosswise thereof to brace them laterally in each direction, substantially as set forth.
2. The herein shown and described folding table comprising a table top divided longitudinally, leg sections having their rails centrally divided and hinged together, and themselves hinged to the table top so as to fold 15 close upon the said table top, the said leg sec-

tions having lateral extensions, side rails hinged to the table top and having notches in their inner sides to receive and embrace the 20 sides of the leg sections at their upper ends, and braces pivotally secured between their ends to notches provided in the upper edges of the said side rails, and adapted to be turned crosswise of the rails to brace them laterally 25 in each direction, substantially as set forth.

In testimony that I claim the foregoing as my own I have hereto affixed my signature in the presence of two witnesses.

VAN CURTIS DODGE.
